UNITED STATES PATENT OFFICE.

MARKS SAMUELS, OF NEW YORK, N. Y.

FOLDING BED.

SPECIFICATION forming part of Letters Patent No. 398,656, dated February 26, 1889.

Application filed June 29, 1888. Serial No. 278,566. (No model.)

To all whom it may concern:

Be it known that I, MARKS SAMUELS, a citizen of the United States, residing at New York, in the county and State of New York, 5 have invented new and useful Improvements in Folding Beds, of which the following is a specification.

This invention relates to an improvement in folding beds, as set forth in the following 10 specification and claims, and illustrated in the accompanying drawings, in which—

Figure 1 is a sectional side elevation of a bed open, the section being taken in the plane $x x$, Fig. 2. Fig. 2 is a plan view of Fig. 1, the 15 mattress being removed. Fig. 3 is a section in the plane $y y$, Fig. 2. Fig. 4 is a view similar to Fig. 1, the bed being closed. Fig. 5 is a section in the plane $v v$, Fig. 2. Fig. 6 is a section in the plane $w w$, Fig. 2. Fig. 7 20 is a sectional side elevation of a part of a bed open, showing a modified form of pivot. Fig. 8 is a view similar to Fig. 7, the bed being closed. Fig. 9 is a section in the plane $u u$, Fig. 7. Fig. 10 is a detail view of a pivot 25 shown in Fig. 7.

Similar letters indicate corresponding parts.

In the drawings, the letter A indicates a support on which swings the bed portion. Said bed portion has two sections, B C, one of 30 said sections being constructed to slide upon the other section. Suitable ways, E, secured to one of the sections and engaging slots or guides on the other section, enable the sliding section C to slide or move.

35 D is the foot-board.

A link, F, is jointed at G to the support A and at H to the section C. Two links are shown in the drawings connected to the sides of the section C; but one link connected to 40 the section C at or near its center will answer the same purpose.

When the bed portion B C is swung down or opened, as seen in Fig. 1, the link F will extend or slide the sliding section C from the 45 position shown in Fig. 4 to the position shown in Fig. 1, thus extending or lengthening the bed portion and making it long enough to accommodate tall persons. When the bed is closed, the link F draws or moves the section 50 C to the position shown in Fig. 4, thus shortening the bed portion and causing the bed

portion when closed to occupy but a small height as compared with the length of the bed portion when opened. The bed, when closed, can thus be set into low niches or 55 small compartments or closets, which is of advantage in limited quarters—such as tenement-houses.

The mattress I is secured at one end to the section B. Intermediate supports or springs, 60 K, may be applied for the mattress. The other end of the mattress is secured to a frame, L, pivoted at M to the section B. When the bed is open, the free portion of the frame L is swung toward the foot-board D, 65 and is held in position by a suitable holding device, such as a spring-catch, N. The mattress I is thus held extended. When the bed is closed, the frame L is released from the catch N and is swung or folded to the position shown in Fig. 4, thus allowing the sliding bed portion C to move to the position shown in Fig. 4 when the bed is closed.

Legs O, for supporting the free part of the bed portion, are shown adapted to slide along 75 ways P. Recesses Q, Fig. 5, in the legs are intended for reception of spring-catches S, which hold the legs O in the proper position. A finger button or handle, T, enables the catch S to be operated. When the bed is 80 closed, the legs O can be slid into the bed along the ways P, so as to be concealed from view. When the bed is open, the legs O should be in position to support the free end of the bed portion, as seen in Fig. 1. 85

Pivots U connect the bed portion to the support A, and in Figs. 1, 2, and 4 said pivots are shown in the form of pins. In Figs. 7 to 10 said pivots are shown in the form of disks U, adapted to turn in lugs or channels V, and 90 said disks and channels enable the bed portion to be easily moved, as said disks can be made to turn easily in the channels.

What I claim as new, and desire to secure by Letters Patent, is— 95

1. The combination, in a folding bed, of a support, a swinging bed portion composed of an inner section pivoted to the support and an outer section sliding on the inner section, and a link pivoted at one end to the support 100 and at its other end to the sliding section to slide the latter outward when the bed portion

is swung to a horizontal position, substantially as described.

2. The combination, in a folding bed, of a support, a swinging bed portion comprising an inner section pivoted to the support and an outer section sliding on the inner section, a link pivoted at one end to the support and at the other end to the sliding section, a folding frame on the inner section, a mattress connected with the inner end of the inner section and with the folding frame, and a catch for holding the mattress and folding frame extended, substantially as described.
3. The combination, in a folding bed, of a

support, A, a bed portion pivoted to the support and carrying at its outer end the sliding spring - impelled catches S, having finger-pieces T, and the sliding legs O, having upper and lower recesses Q, substantially as described.

In testimony whereof I have hereunto set my hand and seal in the presence of two subscribing witnesses.

MARKS SAMUELS. [L. S.]
